ROTARY LAWN MOWER

Henry L. Heineke, Springfield, Ill.

Application February 23, 1954, Serial No. 29,141

Term of patent 14 years

(Cl. D40—1)

FIG. 4.

FIG. 5.

Fig. 1 is a top plan view of a rotary lawn mower embodying my new design;

Fig. 2 is a side elevation thereof;

Fig. 3 is a front elevation thereof, showing however only a portion of the handle;

Fig. 4 is a bottom plan thereof; and

Fig. 5 is a rear elevation, the handle likewise being broken away.

The essential features of the design reside in the portions shown in full lines.

I claim:
The ornamental design for a rotary lawn mower, substantially as shown and described.
